BOWLING ALLEY DRESSING OIL APPLICATOR
Daniel Mitchell, 2522 Honolulu Ave., Montrose, Calif.
Filed May 31, 1961, Ser. No. 145,011
19 Claims. (Cl. 15—529)

This invention relates to the art of applying dressing material to smooth surfaces over which game pieces are to be projected and, more specifically, to a device for dressing the playing surfaces of bowling alleys, although not necessarily restricted thereto.

It is well known that the playing surface of a bowling alley requires it be given careful maintenance to insure that the bowling balls have a flat and uniform surface over which to travel. The surface itself must not only be free from defects, such as dents or low spots, but also must present an area having a uniform rolling or sliding surface which desirably is contributed by a (renewable) dressing or coating which should be of uniform thickness over the length traversed by the bowling ball.

Various devices for applying such a dressing have been proposed and tried. Often a dressing solution is sprayed onto the playing surface and spread about by a flat surfaced member; however, the surface is not uniformly covered by the spray and such initial deposits of dressing liquids then are not easily spread out to secure a perfectly uniform surface layer.

Accordingly, an object of my invention is to provide a device by which the dressing solution is applied as a uniform film over the width of the playing surface of the bowling alley and promptly thereafter wiped over by a sliding member engaging the deposited layer only to insure that no high spots may remain therein.

A further object is to provide a playing surface dressing device in which the dressing solution is supplied to a soft surfaced member as it is rolled over the playing surface, such solution extending substantially across the length thereof, with the dressing solution being automatically delivered as a continuous thin film to the rotating face so as to cause the soft surfaced member to deposit the dressing as a film of uniform and minimum thickness onto the playing surface while being rolled forwardly thereover. Yet another feature interrupts the wick feed when the applicator roller is elevated from rolling contact with the playing surface.

Another object of the invention is to transfer the dressing solution from a tank to a member rolled over the playing surface, by capillary action through a fabric feed member selectively withdrawable from operative contact with the applicator roller.

A still further object is to provide a playing surface dressing device of simple and efficient design comprising a plurality of components advantageously mounted on a frame and easy of fabrication from inexpensive materials, such as wood and metal, the components also being of simple form readily attached to or removed from the frame in assembling the device or adjusting the positions of the components on the frame.

Yet another purpose is to provide the wiping member with a tensioned, face-covering of strip or sheet material adapted to have successive clean or unused areas of the strip disposed in frictional juxtaposition with the wiper face. If desired, such movement of the sheet may be intermittently effected by pedal manipulation of a drive sprocket connected to a draw roll, which winds upon itself the used strip of material initially derived from a replaceable supply roll.

A further object is to effect the provision of a sliding wiper member or drag bar which is selectively disposable in full face-contact with the playing surface or alternately is disposable in edge contact therewith; a third position

2

wherein the wiper is completely elevated off the playing surface can be effected by simply tilting the frame a small amount toward the applicator roller.

An additional purpose is to provide a balanced assembly which by means of a rigid handle member can be readily tilted toward the roller member or toward the wiper member so as to hold the other member up off the floor while moving the contacting member functionally along the playing surface. Still another feature is the provision of means, exemplified by a forward pair of runners adapted selectively to elevate the forward portion of the assembly, including the applicator roller, off the playing surface and automatically interrupt the wick feed of dressing solution thereto.

Other objects, advantages, and features of invention may appear from the accompanying drawings, the subjoined detail description, and the appended claims.

FIGURE 1 is a top plan view of my device with a portion in the lower right broken away to show internal construction;

FIGURE 2 is a front elevational view thereof;

FIGURE 3 is a side elevational view as seen from the right of FIGURE 1;

FIGURE 4 is a vertical sectional view thru the device as viewed in FIGURE 3 but with the oil-applying roller elevated from the floor by the downswing forward runners, and also with the oil supplying wick member raised from contact with the roller, the rear drag bar thus being disposed in maximum surface contact for wiping the floor;

FIGURE 5 is an elevational view of the rear of half of the forward housing showing one of the pair of oil supply tanks as seen along the line 5—5 of FIGURE 4;

FIGURE 6 is a longitudinal sectional view taken thru the oil supply member along the line 6—6 of FIGURE 4;

FIGURE 7 is a longitudinal sectional view thru one end of the wiper member or drag-bar taken along the line 7—7 of FIGURE 4; and

FIGURE 8 is an axial sectional view thru the foot ratchet and adjacent draw roll of wiping material, the unwinding sheet of which is intermittently moved across the contact face of the drag-bar from the supply roll as seen in FIGURE 3.

In the present embodiment of the invention, there is a frame or casing 10 consisting of a forward, transverse, flat top, housing 11 and vertically disposed, rearward extending side arms 12, 13 which serve as supports for a rear pair of transverse strip-carrying rolls 70, 72 and for the mutually parallel drag-bar or wiper member 43, as subsequently described. An angularly rising, operating handle 14 is rigidly secured to the top of the forward housing 11 by a mounting bracket 15. A forward, transverse roller member 17 is journaled between a parallel pair of vertically downward projecting suspension arms 16, 18 which are secured to inset sides of the frame 10. The roller 17 is thus somewhat shorter than the maximum width of the frame and is constructed of an inner tubular element 19 rotatably mounted by axial trunnions 20, 21 to the arms 16, 18 and provided with a surrounding roll of resilient character such as sponge rubber 22. A pair of arcuately swinging struts 23, 24 are each pivotally connected at one end 25, 26 to the respective suspension arm 16, 18, and carry roller support means such as a floor-contacting wheel 27, 28 on their free end. When the forward roller 17 is supported upon the floor 9, the wheels 27, 28 are in trailing or non-supporting position (FIG. 3) and their parallel struts are angularly disposed. However, each pivoted strut 23, 24 also carries a transverse detent arm 29 (FIGS. 3—4), the rear inturned end 30 of which is disposed to abut against the rear vertical edge of the ad-

jaçent suspension arm 16 or 18 so as then to retain the struts 23, 24 upright parallel to the adjacent arm 16 or 18, thus raising the roller 17 off the floor 9 and supporting the forward portion of the tilted frame 11 solely on the wheels 27, 28. In such position, the assembly can be drawn by the handle 14 to the rear (i.e. to the right in FIGURE 4) for a purpose to be described. Upon reversal of direction, the unit drops down upon the forward roller 17 and the pivoted wheels revert to their trailing position of FIGURE 3, the detent arm 29 being 10 out of engagement with the uprights 16, 18.

The rear portion of the frame or casting 11 has dependently affixed between the lower margins of the sides 12, 13 as by screws 57, 58 along each side, a transverse wiper member 43 constructed of a longitudinal, inverted U-shaped, cross channel 59 to the lateral arms of which are secured a flat mounting plate 60, as by screws 61, 62. The latter also attaches a transverse backing member 63, of wood or the like, to which is affixed as by adhesive or cement, a transverse wiping element 64 of compressible material as sponge rubber or the like having a transversely continuous face. The compressible wiper 64 is somewhat wedge shaped in transverse section, with a normally angularly disposed, contact surface 65 adapted to be disposed in juxtaposition to the flooring surface 9, at such time as the forward portion of the frame is elevated, as by being held up by the runners 27, 28. Alternately when the forward, applicator roller 17 is self-supported upon the playing surface 9, the sliding wiper 43 is accordingly tilted forward (FIG. 3 as compared with FIG. 4) so that only the forward portion of lesser floor-contact area or relatively narrow lead edge of the generally flat bottom contact face wipes the surface. As a third position when it is desired to move the device along the playing surface with only the applicator roller 17 functionally contacting the same, the whole frame 11 can be tilted forward by slight elevation of the rigid handle 14, so that the entire contact face 65 of the drag bar is elevated completely off the floor.

In this connection it has been found that it is particularly effective to dispose successive clean areas of a sheet or strip of wiping material 68 (which may be any suitable, flexible, somewhat absorbent material, such as paper or cloth) frictionally overlying the contact surface 65 of the wiper member 43 so as to be pressed against the playing surface 9 by more or less resilient pressure or weight of the sponge rubber 64 and associated structures. In such manner, the sliding or wiping action of the sheet material 68 picks up any excess of liquid floor dressing laid down by the applicator roller 17. In addition, even at times other than the application of fresh dressing material, the wiper 64 with its facing strip 68 may be dusted across the playing surface to wipe it clean of extraneous matter whether moist or dry.

A pair of rollers 70, 72 are rotatably mounted between opposite sides 12, 13 of the frame, generally parallel to the wiping member 43 and at somewhat of an elevation thereabove, whereby sheet material wound about the supply roll 70 may be drawn down to underlie the contact face 65 and thence directed upward therefrom to the draw roller 72. Each of the pair of rollers is mutually restrained against free rotation so as to maintain the facing sheet 68 under tension and thereby hold it relatively snugly against the contact face 65. Simultaneous tensioning of the two rollers 70, 72 is simply effected by a corresponding pair of split collars 71, 73 (FIG. 1) mounted on the respective shafts 66, 67, with their split ends held together and inter-connected by a transverse compression or coil spring 69.

From time to time it is desired to withdraw the soiled area of the strip 68 from the contact surface 65 by winding it on the draw roll 72, and for this purpose there is provided a pedal operated, sprocket drive 74 consisting

essentially of a pivot arm 76 mounted at 78 and tensioned upward by spring member 80 to normal abutment with a generally horizontal detent pin 82. A dependent dog 84 is disposed to contact, in driving relation, successive sprockets of a rotary plate 86 affixed to the shaft 67 of the draw roll, so that a depression of the foot pedal 90 will drive the roll 72 in the desired direction of winding or drawing the sheet material 68 to locate a clean or unused area of the wiping material 68 adjacent the contact face 65 of the draw bar. This arrangement allows the substitution of different sheets or rolls of facing material for the draw bar 43 so that the sponge rubber body 64 is kept relatively clean. However, alternately, the sheet material can be eliminated, either from time to time or permanently, and direct contact effected between the wiping element 64 and the playing surface 9, in which case the detachable mount of the drag bar assembly is itself replaced from time to time by merely unfastening the screws 61, 62. For such use, the wiper body 64 is usually provided with a covering 56 of flannel or the like. Also other material than sponge rubber may be used for the wiping element 64, particularly when used to wipe more abrasive surfaces (e.g. concrete or stone) than that of a bowling alley.

The upper transverse face 11 of the casting, along its rear margin extends vertically downward to provide a cross-member 92, to the posterior or outer face of which is hingedly mounted as by upright hanger straps 94, a transverse bracket arm 96 (FIG. 5) having forward extending arms 98, 99 between which one or more supply tanks 33 are pivotally suspended. As here illustrated, an independent supply tank is provided for each half of the wiping area of the roller 17, since it is often desirable to treat (more frequently) one half of the playing surface, such as the right half which receives the most use. Each container 33 is conveniently a cylindrical chamber having an upper supply nozzle and closure 100, and being mounted by its ends lengthwise between the arms 98, 99 which are held in a forward position by a spring 97. Each container 33 is generally radially traversed by a longitudinal, outward extending, generally rigid plate 102, the outward projecting portion of which is overlayed with a downturned L-shaped shield 104 affixed to the cylindrical body 33 and connected by a helical spring 106 to the cross member 92 so as jointly to tilt upward the composite unit 33-104. The stiffening plate 102 is sandwiched within an elongated wick element 37 which thus extends into the interior of the tank 33 and by capillary action draws out and transfers liquid dressing material from its exposed underface 42 to the outer facing cover 32 of the forward applicator roller 17.

As illustrated in FIGURE 4, the spring 106 in the absence of any opposing force, holds the transfer face of the wick element 42 elevated from contact with the applicator roller. Accordingly, in order to maintain contact of the wick with the applicator roller 17 and provide a continuous supply to the rotating face 32 during operation, there is provided a detachable follower 108, terminally mounted upon a lever rod 110 which is apertured for mounting upon a longitudinally spaced pair of laterally projecting pins 112, 114 (FIGS. 6 and 3) disposed for thrust insertion and extending from the outer annular end 116 of the container 33. The aligned engagement pins 112, 114 are so placed that pressure of the floor surface 9 against the roller 108 causes the lever arm 110 to swing the container 33 and wick 42 down to be slidingly engaged by the rotating applicator covering 32, overcoming the opposing tension of the spring 106. This continues only as long as the follower 108 is held against the floor 9. For functional disengagement of the wick assembly 104, the roller 108 and lever arm 110 may be simply withdrawn from the attachment pins 112, 114, and the unit 108, 110 thrust beneath a resilient clasp.

member 118 atop the casting for retention until further use. Alternately, when the follower remains attached to the container wall 116 and the frame raised upon the runners 27, 28 (elevating the applicator roller 17 from floor contact) the wick 42 is no longer held against the applicator covering 32 by the lever arm 110 but the container 33 is rotated upward by the spring 106.

I claim:

1. In a floor treating device of the character described, having a frame carried by a transverse, cylindrical, applicator roller and a generally parallel, wiper member each adapted selectively by tilting of said frame to functionally contact the floor as the device is moved along, the improvement comprising in combination therewith: a pair of wheels laterally spaced apart and carried by said device adjacent opposite ends of said roller, each wheel being mounted on a strut movably secured to said device for alternate location between extended and retracted positions wherein respectively the floor-engaged wheels support said frame with the roller elevated off the floor, and wherein the retracted wheels leave the roller self-supporting on the floor; a container for a supply of liquid dressing movably mounted on said frame adjacent to said roller, wick means extending from said container for supplying liquid dressing to said roller, means for moving said container in one direction to disengage the wick from the roller and means extending from the container and adapted to engage a contacted floor when the roller is self supporting on the floor to move the container in the opposite direction to cause the wick to contact the roller.

2. In combination with a floor treating device of the character described, having a frame carried by a transverse, cylindrical, applicator roller, a floor contacting wiper member mounted on said frame generally parallel to said roller and being provided with two downwardly facing angularly related front and rear floor contacting surfaces, an operating handle rigidly secured to said frame, said surfaces being arranged to alternately engage a floor being treated by moving said handle to tilt the rear end of the frame either upwardly or downwardly as the device is moved along the floor, said front surface being positioned to contact the floor when the applicator roller is in contact therewith, a pair of supply and draw rolls respectively disposed along opposite longitudinal sides of said wiper member and adapted to dispose a tensioned sheet of wiping material jointly between them frictionally overlying both floor-contact faces of said member, and operative means for intermittently drawing a fresh area of said material over said contact face of the wiper member from the supply roll to the draw roll.

3. In combination with a floor treating device of the character described, having a frame carried by a transverse, cylindrical, applicator roller, a floor contacting wiper member mounted on said frame generally parallel to said roller and being provided with two downwardly facing angularly related front and rear floor contacting surfaces, said surfaces being arranged to alternately engage a floor being treated by tilting the rear end of the frame either upwardly or downwardly as the device is moved along the floor, said front surface being positioned to contact the floor when the applicator roller is in contact therewith, a pair of wheels laterally spaced apart and carried by said device adjacent opposite ends of said roller, each wheel being mounted on a strut movably secured to said device for alternate location between extended and retracted positions wherein respectively the floor-engaged wheels support said frame with the roller elevated off the floor, and wherein the retracted wheels leave the roller self-supporting on the floor; fluid supply means carried by said frame, another floor-contact element carried by the device in position to be operatively floor-engageable only when said roller is floor-supported, and which in such position is adapted to activate continuous,

capillary flow of liquid floor dressing to said roller from the fluid supply means; a pair of supply and draw rolls respectively disposed along opposite longitudinal sides of said wiper member and adapted to dispose a tensioned sheet of wiping material jointly between them frictionally overlying the floor-contact face of said member, and operative means for intermittently drawing a fresh area of said material over said contact face of the wiper member from the supply roll to the draw roll.

4. In a floor treating device of the character described, having a frame carried by a transverse, cylindrical, applicator roller and a generally parallel, wiper member each adapted selectively to functionally contact the floor as the device is moved along, the improvement comprising in combination therewith: floor-contact means for elevating said applicator roller off the floor and simultaneously locating said wiper member at a position disposing a maximum area for sliding contact with the floor, a container for a supply of liquid dressing movably mounted on said frame adjacent to said roller, wick means extending from said container for supplying liquid dressing to said roller, means for moving said container in one direction to disengage the wick from the roller and means extending from said container and adapted to engage a contacted floor to move the container in the opposite direction to cause the wick to contact the roller when the roller is in floor engagement.

5. A device for applying a liquid dressing to the playing surface of a bowling alley, comprising in combination: a frame having a leading and a following end; a freely rotatable cylindrical roller extending across the leading end of the frame and having an absorbent covering disposed in contact with said playing surface and adapted to transfer a predetermined thickness of liquid dressing to the surface by rolling registration therewith; a container for a supply of liquid dressing mounted on said frame; transversely disposed wick means substantially co-extensive with the length of said absorbent covering and adapted to convey continuously a measured amount of said dressing from the container lengthwise along the coated cylindrical roller in amount corresponding to the quantity adapted to be continually transferred to the playing surface upon rotation of the roller; said wick being extended into said container, said container being movably secured to said frame, means for moving the container and wick alternately as a unit in one direction to permit the wick to contact the roller and means to move the container and wick unit in the opposite direction to disengage the wick from the roller, a wiper member mounted across the following end of the frame for sliding contact with the playing surface; and roller support means for selectively elevating the rotatable cylinder from floor contact and thus disposing only the wiper member in sliding registration with said floor.

6. The device of the preceding claim 5 which additionally contains a draw sheet of wiping material removably mounted across the contact surface of said wiper member.

7. The device of the preceding claim 5 which additionally contains a pair of supply and draw rolls respectively disposed along opposite longitudinal sides of said wiper member and adapted to dispose a tensioned sheet of wiping material jointly between them frictionally overlying the floor-contact face of said member, and operative means for intermittently drawing a fresh area of said material over said contact face of the wiper member from the supply roll to the draw roll.

8. A device for applying a liquid dressing to the playing surface of a bowling alley, comprising in combination: a frame having a leading end and a following end disposed transverse to the playing surface; a freely rotatable cylindrical roller extending across the leading end of the frame, having an absorbent covering disposed in contact with said playing surface and adapted to transfer a predetermined thickness of liquid dressing to the surface

by rolling registration therewith; a container for a supply of liquid dressing pivotally mounted on such frame adjacent said cylindrical roller and functionally associated longitudinally extending wick means adapted to continuously convey a measured amount of said dressing from the container lengthwise along the covered cylindrical roller in amount corresponding to the quantity adapted to be continually transferred to the playing surface upon rotation of the roller; resilient means adapted normally to hold said wick means disengaged from said cylindrical roller; a floor contacting runner adapted selectively to maintain said wick means and roller in functional engagement by positioning the pivoted container as long as the roller and runner are both directly supported upon the floor; a wiper member mounted across the following end of the frame for sliding contact with the playing surface, having an angularly disposed, compressible floor-contact surface adapted alternately for edge contact and for complete juxtaposition with the surface depending upon angular disposition of said frame; an upstanding, rigidly mounted handle secured to the frame, by use of which the device can be moved along the playing surface with both its cylindrical roller and its wiper member in functional contact therewith, and alternately, by a small amount of tilting of the frame by the handle toward one member or the other, permitting the device to be moved along the surface supported only by such one member thus disposed in functional engagement with said surface; a pair of supply and draw rolls rotatably mounted between said frame arms and respectively disposed adjacent opposite longitudinal sides of said wiping member, and adapted to dispose a tensioned sheet of wiping material jointly between them frictionally overlying the floor-contact face of said member; and sprocket means carried by said frame, and adapted by driving connection with said draw roll for intermittently drawing a fresh area of said sheet material over the contact face of the wiping member from the supply roll to the draw roll.

9. A device for applying a liquid dressing to a floor and comprising in combination: a frame having a leading end and a following end; an applicator roller extending across the leading end of the frame, having an absorbent covering disposed in contact with said floor and adapted to transfer a predetermined thickness of liquid dressing to the floor

surface by rolling registration therewith; a container for a supply of liquid dressing mounted on said frame adjacent said roller, and functionally associated, longitudinally extending transversely disposed wick means substantially coextensive with the length of said absorbent covering and adapted to continuously convey by capillary action a measured amount of said dressing from the container lengthwise along the covered roller in amount corresponding to the quantity adapted to be continually transferred to the floor surface upon rotation of the roller when the roller is in contact with the floor surface a spring means for moving said container to a position to disengage the wick from the roller and other means depending from the container positioned to engage a contacted floor for moving the container to a position to cause the wick to contact the roller.

10. The device of the preceding claim 9 which also includes a wiper member mounted across the following end of the frame for sliding contact with the floor, having an angularly disposed, compressible floor-contact surface adapted alternately for edge contact and for complete juxtaposition with the floor depending upon angular disposition of said frame; and roller support means for selectively elevating the rotatable cylinder from floor contact and thus disposing the wiper member in complete juxtaposition for sliding registration with said floor, with said wick means disengaged from said roller.
